UNITED STATES PATENT OFFICE.

HJALMAR SWANSON, OF CHICAGO, ILLINOIS, ASSIGNOR TO CUMMINS PERFORATOR COMPANY, OF CHICAGO, ILLINOIS, A CORPORATION OF ILLINOIS.

HAND PERFORATOR.

Application filed May 31, 1921. Serial No. 473,693.

To all whom it may concern:

Be it known that I, HJALMAR SWANSON, a citizen of the United States, residing in Chicago, in the county of Cook and State 5 of Illinois, have invented a new and useful Improvement in Hand Perforators, of which the following is a specification.

This invention relates to hand perforators, and has for its general object to provide 10 a simply constructed though highly efficient device of this character, which may be carried around on the person of the operator, and which embodies, among other features, provision for punching changeable-data 15 preferably in combination with the punching of non-changeable-data. By the invention, a salesman, for example, or other operator, may punch on successive slips of paper, such as sales tickets, different data, 20 as successive numbers indicating successive sales, combined with the punching of fixed data on each sales ticket, the fixed data indicating the particular salesman making the sale. When utilized in the manner above 25 set forth, the invention provides perforating equipment that is especially suitable for large sales organizations, such as department stores, in that the use of the improved hand perforator will furnish a practically 30 unalterable record of the sales made by each individual salesman.

In addition to the general objects recited above, the invention has for further objects such other improvements and advantages in 35 construction and operation as may be found to obtain in the structures and devices hereinafter described or claimed.

In the accompanying drawings, forming 40 a part of this specification and showing, for purposes of exemplification, a preferred form and manner in which the invention may be embodied and practiced, but without limiting the claimed invention specifically to such illustrative instance or instances:

45 Figure 1 is a top plan view of a hand perforator constructed in accordance with the improvements of the present invention;

Fig. 2 is a side elevation of the same;

Fig. 3 is a bottom plan view of the same;

50 Fig. 4 is a longitudinal horizontal section of the hand perforator taken on the line 4-4 of Fig. 2;

Fig. 5 is a longitudinal vertical section of the hand perforator taken on the line 55 5-5 of Fig. 1;

Fig. 6 is a transverse vertical section of the hand perforator taken on the line 6-6 of Fig. 2;

Fig. 7 is a detailed end elevation of the hand perforator; 60

Fig. 8 is a detailed side elevation of the same; and,

Fig. 9 is a longitudinal horizontal section taken on the line 9-9 of Fig. 5.

The same characters of reference indicate 65 the same parts in each of the several views of the drawings.

In the illustrated embodiment of the invention, the hand perforator is especially designed for being used in the manner above 70 specified and, for convenience, the present description will be confined to this use of the invention. Features of construction of the hand perforator are, however, capable of other applications; hence, the scope of the 75 invention is not confined to the specific use and specific embodiment herein described as an illustrative example.

Referring to the drawings: The hand 80 perforator embodies in its construction a pair of movable jaw members 11 and 12 respectively provided, at one end, with handle grips 13 and 14, and pivoted together, at the opposite end at 15. A spring 16, the opposite ends of which seat in sockets 17 85 and 18 provided in the members 11 and 12 maintains said members normally apart from each other, a position in which the punches are retracted from the dies. The sheet or sheets of paper to be punched are 90 inserted in an open ended slot 19, extending longitudinally in the jaw member 12. Seated in said member 12 at the bottom of the slot 19 is the die plate 20, the dies of which communicate with an opening 21 below the die plate for discharge of the 95 punched particles of paper.

In the present instance, the die plate 20 is provided with two series of dies A and B, the former cooperating with a series of 100 punches for perforating the fixed-data and the latter co-operating with a series of punches for perforating the changeable-data. The fixed-data dies A are furthermore divided into two groups *a* and *a'* for co-operation with corresponding groups of the fixed-data punches, each such group of punches co-acting with its corresponding group of dies to perforate a character of the fixed-data, such as a digit of a two digit 110

number designating, for example, the particular person operating the punch. The changeable-data dies are also sub-divided into two groups b and b' , each group co-operating with a corresponding group of the changeable-data punches to perforate a character.

The punches 22 are divided into two series A' and B' and the series A', B' are 10 respectively sub-divided into groups of punches a^2 and a^3 and b^2 and b^3 , the groups a^2 and a^3 co-operating respectively with the groups of dies a and a' and the groups b^2 and b^3 co-operating respectively with the 15 groups of dies b and b' , in the manner above stated. Both series of punches A' and B' extend into a chamber 23 provided in the jaw member 12, and the lower ends of said punches, when in advanced position with 20 respect to their corresponding dies extend through the perforate guide plate 24 located below the chamber 23 and forming the top of the paper-receiving slot 19. When in the retracted position, the upper ends of 25 the punches extend through a top guide plate 25, which forms the top of the chamber 23. The punches 22 are further guided in their advancing or retracting movement, by a soft metal filling 26 located above the lower 30 guide plate 24.

The punches A' of the fixed-data series are operated by a fixed or non-adjustable matrix 27, which preferably consists of a plate fixed to the lower face 28 of the jaw member 11 and movable to advance the fixed-data punches A' into their corresponding dies A, during the operation of squeezing together the handle grips 13 and 14 of the two jaw members 11 and 12. In the 35 form shown the matrix 27 is reversely socketed for each group of punches a^2 and a^3 so that it will not operate those punches of the groups which are not required for perforating the particular characters desired. 40 During the operative movement of the matrix 27, the punches not required pass idly through the reverse sockets in the fixed matrix and only those punches which are required for punching the characters desired 45 are engaged by the face of the matrix and advanced into co-operation with their respective dies. 50

The changeable-data punches B' are operated by adjustable or revoluble matrices 55 29, there being one matrix for each group b^2 and b^3 of said punches B'. The adjustable matrices 29 are preferably constituted of rings which revolve upon a fixed arbor 30 secured in the bifurcated portion of the 60 jaw member 11. Each matrix ring 29 is preferably provided with a series of matrix faces 31, preferably ten in number, one for each of the nine digits and one for zero, the matrix faces 31 being also reversely socketed, so that they will not operate those

punches of the group which are not required for printing the particular character desired. The matrix rings 29 are held in proper position for the operation of each of their matrix faces by positioning members 32 which 70 are moved by springs 33 respectively into one of a series of sockets 34 formed in the inner circumferential portion of each matrix ring. When the positioning members 32 are seated within sockets 34 of their respective 75 matrix rings, a matrix face 31 of each ring is in proper position for operating its corresponding group of changeable-data punches.

Pivots secured to the opposite side faces 80 of the jaw member 11 are spring arms 35, respectively provided with lugs 36 and with finger knobs 37. As shown in Figs. 2 and 8, slots 38 are provided in the opposite side walls of the member 11, said slots exposing 85 seriatum two adjacent sockets of a series of ten sockets 39 provided respectively in the opposite outside faces of the matrix rings 29. With this construction, the spring arm 35 corresponding to either matrix rings 29 may 90 be operated to insert the lug 36, in one or the other of the exposed sockets 39 and, by a short pivotal movement of the arm 35 the matrix ring may be moved in either direction to move one matrix face out of operative position and to position another for a succeeding operation of the perforator. Preferably each slot 38 is dimensioned to restrict the movement of the arm 35 to a degree just sufficient to substitute an adjacent 95 matrix face for a matrix face previously operated. However, in any event the spring 100 pressed positioning members 32 will operate to prevent overthrow, during the operation of changing a matrix face.

The positioned matrix faces 31 of the rings 29 are advanced to push forward the selected punches of the two groups b^2 and b^3 of the series B', when the handles 13 and 14 of the jaw members 11 and 12 are 105 squeezed together, the punching operation effected by the adjustable matrix taking place concurrently with the punching operation effected by the fixed matrix face 27. As the positioned matrix faces 31 advance 110 the selected punches into their corresponding dies, those punches of the groups b^2 and b^3 which are not required to effect the perforation of the particular character remain 115 stationary, the reverse sockets in the positioned matrix faces 31 moving to position the upper ends of the inoperative punches in said sockets, as shown in Figs. 5 and 6.

When pressure is released from the handles 13 and 14 of the jaw members 11 and 12 the spring 16 restores said jaw members to their retracted position. The movement of the members 11 and 12 to such retracted position is accompanied by a concurrent restoration of the previously op- 120 125 130

erated punches of both series A' and B' to their normal position. For this purpose, each punch 22 is provided with a fixed collar 40, adapted to be engaged by the upper 5 face of a perforate plate 41 through which the several punches 22 extend. The plate 41 is supported by side members 42 carried by the jaw member 11, and as the latter moves away from the other jaw member 12 the 10 upper face of the plate engages the collars 41 of the several previously operated punches and restores them to their normal retracted position.

The invention as hereinabove set forth is 15 embodied in a particular form of construction but may be variously embodied within the scope of the claims hereinafter made.

I claim:

1. In a hand perforator, in combination: 20 a pair of jaw members pivotally connected together; dies carried by one of said members and disposed in a series of fixed-data dies and a series of changeable-data dies; two series of punches respectively corresponding to the said two series of dies, a 25 fixed matrix carried by the other jaw member for operating said fixed-data punches; a revoluble matrix member also carried by said other jaw member and provided with a 30 plurality of matrix faces each of which may operate the changeable-data punches; the fixed matrix and a matrix face of said revoluble member being operated to effect the concurrent operation of both series of 35 punches, during the movement of said jaw members toward each other; a pin for engagement with said revoluble matrix member for positioning said matrix faces; and means for yieldably maintaining said pin 40 in operative position; substantially as specified.

2. In a hand perforator, a pair of manually-operable members pivotally connected together for operative movement toward 45 each other, combined with dies carried by one of said members, a plurality of selectively operable punches adapted to co-operate with said dies, selective matrix means carried by the other member for operating 50 said punches during the manual operation of said members; and a handle pivotally mounted on one of said members for imparting a stepped movement to said matrix means; substantially as specified.

55 3. In a hand perforator, in combination: a pair of manually-operable members pivotally connected together; dies carried by one of said members; a series of punches respectively co-operable with said dies, an adjustable matrix element carried by the other member and provided with a plurality of matrix faces each of which may operate 60 said punches; a matrix face of said adjustable matrix element being operated to effect

the operation of said punches, during manual movement of said members toward each other; a manually-controlled arm pivotally mounted on said other member for adjusting said matrix elements to change the positions of said matrix faces; and means 70 for moving said manually-operable members to retract the previously operated punches from their dies, substantially as specified.

4. In a hand perforator, in combination: a pair of manually-operable members pivotally connected together; dies carried by one of said members; a series of punches respectively co-operable with said dies, an adjustable matrix element carried by the other member and provided with a plurality of 80 matrix faces each of which may operate said punches; a matrix face of said adjustable member being operated to effect the operation of said punches, during manual movement of said members toward each other; manually-controlled means pivotally mounted on said other member for adjusting said matrix members to change the positions of said matrix faces; and means for moving said manually-operable members to retract the 90 previously operated punches from their dies; substantially as specified.

5. In a hand perforator, in combination: a pair of manually-operable members pivotally connected together; dies carried by 95 one of said members; a series of punches respectively co-operable with said dies; an adjustable matrix element carried by the other member and provided with a plurality of matrix faces each of which may operate said punches; a matrix face of said adjustable element being operated to effect the operation of said punches, during manual movement of said members toward each other; means for moving said manually-operable members to retract the previously operated punches from their dies; and means pivoted to said other member and engageable with said adjustable matrix element for 100 positioning said matrix faces; substantially as specified.

6. In a hand perforator, in combination: a pair of manually-operable members pivotally connected together; dies carried by one of said members; a series of punches respectively co-operable with said dies; an adjustable matrix element carried by the other member and provided with a plurality of matrix faces, a matrix face of said adjustable element being operated to effect the operation of said punches, during manual movement of said members toward each other; and means carried by said other member and engageable with said adjustable matrix element for positioning said matrix faces; substantially as specified.

HJALMAR SWANSON.
